UNITED STATES PATENT OFFICE.

THOMAS DANQUARD, OF NEW YORK, N. Y., ASSIGNOR TO THE AUTOPIANO CO., OF NEW YORK,
N. Y., A CORPORATION OF NEW YORK.

TRACKER-BAR-OPERATING MECHANISM.

No. 902,480.

Specification of Letters Patent.

Patented Oct. 27, 1908.

Application filed July 14, 1906, Serial No. 326,162. Renewed August 24, 1908. Serial No. 450,056.

To all whom it may concern:

Be it known that I, THOMAS DANQUARD, a citizen of the United States, residing at New York, in the county of New York and State 5 of New York, have invented a new and useful Tracker-Bar-Operating Mechanism, of which the following is a specification.

My invention relates to that class of mechanical musical instruments and playing 10 attachments in which two tracker-bars are employed, one having a greater range than the other or in other words, being provided with a greater number of air conducting channels, whereby the music sheets of the 15 ordinary kind which do not cover the entire range of a piano can be used on the instrument, and then by means of certain manipulations, the instrument or attachment can be prepared for use with music sheets of a 20 different range.

The principal objects of the present invention are to provide an improved means for accomplishing this result by the use of two tracker-bars connected with the primary 25 pneumatics by connections, parts of which are flexible and having a convenient and simple means for manipulating the tracker-bars so as to insure the opening of the channels of one bar for playing when it is placed 30 in proper position and the simultaneous withdrawal of the other from playing position and the effectual closure of the channels thereof.

Reference is to be had to the accompanying drawing in which, Figure 1 is an elevation of a structure illustrating the principle of my invention. Fig. 2 is a vertical sectional view of the same. Fig. 3 is a sectional view on the line 3 of Fig. 2. Fig. 4 is a sectional view on the line 4 of Fig. 2, and Fig. 5 is a fragmentary view similar to Fig. 2 showing the parts in a different position.

For accomplishing the above mentioned results, I have provided two tracker-bars 10 and 11, each adapted to be moved into the usual position of the tracker-bar between the two rolls for the music sheet which are intended to be operated in the usual or any desired manner. These two tracker-bars are 15 provided with different numbers of channels, each communicating through a tube 12 with a flexible connection 13, both of the flexible connections corresponding to the same note in the two bars being led to a 20 chamber 14 which communicates through a

tube or passage 15 with the primary pneumatic 16. The primary pneumatics are sufficient in number to accommodate the larger number of channels in one of the bars and they may control the operation of the instrument or attachment in any known or desired manner. 60

It is desired at all times to have one tracker-bar in a position for playing and the other closed so that the air cannot enter its 65 passages. For this purpose, a pair of plates 17 are mounted on frames extending inwardly, one being provided with a stopping surface 18 and the other with a corresponding surface 19. 70

In operation, the tracker-bars are moved from the position shown in Fig. 2 to that shown in Fig. 5 to change the range of the instrument whenever the music sheet to be used is of a different range. 75

It will be noticed that in the construction illustrated, the tracker-bars are moved through an angle of 90 degrees. It is desirable to accomplish this motion by a comparatively short motion of an operating handle and for this purpose I have provided such a handle 20 pivoted in any convenient position and connected by a link 21 with oscillating frame 22, this frame being pivoted on a stud 23 on which is mounted stationary 80 gear teeth 24, constituting a rack or gear segment. 85

Each of the tracker-bars is provided with corresponding gear teeth 25 meshing with the stationary teeth and each one is pivoted 90 on the frame 22 so that it can have a double motion; one with the frame about the studs 23 as a center and the other on its own stud. By such a construction as this, a comparatively rapid motion of the two bars is secured with but a short motion of the lever 20 and in fact, with only a short oscillation of the frame 22. However, as the frame moves about its pivot, the tracker-bars are not only carried with it but on account of the relation 95 of the gear teeth, they are turned in the same direction as the frame is moving, but at a greater speed, on their own pivots. This gives a wide range of motion to the tracker-bars without necessitating the same angular 100 motion of the frame or other support which carries them. With an angular motion of the frame of only a few degrees the tracker-bars are carried around 90 degrees; one from a position in contact with its stopping pad 18 110

or 19 to playing position, and the other from playing position to the other stopping pad. While, of course, it is not necessary that this motion be 90 degrees, this forms a convenient structure and I have so illustrated the invention. It will be obvious, however, that the tracker-bars may be swung through a smaller or greater angle than this, the pads 18 and 19 being correspondingly mounted and the motion of the frame 22 also being modified in proportion. I am also aware that other changes may be made in the construction of the device by any person skilled in the art without departing from the scope of the invention as expressed in the claims.

Having thus fully described my invention, what I claim and desire to secure by Letters-Patent is:—

1. In a device of the character described, the combination of a movable frame, a tracker-bar pivoted on said frame, and means for automatically swinging said tracker-bar on its pivot when the frame is moved.
2. A music playing instrument or attachment having a plurality of tracker-bars mounted to turn on different axes.
3. A music playing instrument or attachment having a plurality of tracker-bars mounted to turn on different axes, and means for swinging the axes and simultaneously turning the tracker-bars thereon.
4. The combination of a tracker-bar, a swinging frame on which said bar is mounted, and means operable by the motion of the frame for swinging the bar through a greater angle than that traversed by the frame.
5. The combination of a tracker-bar, a swinging frame on which said bar is mounted, means operable by the motion of the frame for swinging the bar through a greater angle than that traversed by the frame, said means

comprising stationary gear teeth, and gear teeth connected with the bar and meshing with the first named gear teeth.

6. In a music playing device, the combination of a pivoted frame, and stationary gear teeth, a plurality of tracker-bars pivotally mounted on said frame, and movable therewith, and gear teeth connected with each tracker-bar and meshing with the stationary teeth.

7. In a music playing device, the combination of a pivoted frame, a gear or circular gear segment mounted in stationary position concentric with the pivot of the frame, a pair of tracker-bars pivotally mounted on said frame, and movable therewith, each tracker-bar having a gear segment meshing with the first named segment.

8. The combination of two tracker-bars, a swinging frame on which said bars are mounted, means operable by the motion of the frame for swinging the bars through a greater angle than that traversed by the frame, and a pair of stationary stops for said tracker-bars, each located in position to engage one of the bars when in a certain position.

9. In a music playing device, the combination of a movable frame, a stationary rack or gear segment mounted adjacent thereto, and two tracker-bars each movably mounted on said frame, each tracker-bar having gear teeth for engaging with said rack or segment, whereby when the frame is moved the tracker-bars will be moved in a different way.

In testimony whereof I have hereunto set my hand, in the presence of two subscribing witnesses.

THOMAS DANQUARD. [L. S.]
